ABSTRACT OF THE DISCLOSURE

An ion source for a sputtering apparatus comprising an open cylinder in which at one end a filament cathode is arranged, which is screened by two screening plates at right angles to the axis. An axial magnetic field in the anode of a few hundred gauss brings about a low burning voltage of about 30 to 40 v.

The invention relates to an ion source for slow-ion sputtering, in which the ions are produced in a non-self-sustained discharge occurring at least partly in a magnetic field.

In the arrangement disclosed in British patent specification 1,113,579 the filament cathode of the discharge is arranged in the gas supply chamber which communicates through a small orifice with the sputtering space, where the anode is accommodated. The anode surrounds the material to be sputtered, the target. The objects to be sputtered, the substrate, are disposed at the side of the discharge path around the same. In front of the anode in the discharge space a magnetic field of a few hundred gauss prevails in parallel to the discharge path.

In this arrangement it is difficult to act upon the paths of the sputtered particles by magnetic and/or electric agency independently of the magnetic field in the discharge path. The anode voltage of the discharge is stated to be 60 v.

Although this anode voltage seems to be low, ions may nevertheless occur at the low pressures in the discharge, the velocity of said ions exceeding 50 ev. Such ions release particles from the apparatus, which results in that the ready products exhibit contaminations by these released particles.

From the Swiss patent specification 465,996 there is known a sputtering arrangement in which the ions emanating from an ion source are oriented by an axial magnetic field to the sputtering plates. The ion source comprises a magnetic lens for guiding the ions. The filament cathode of the ion source is located, however, in a space free of a magnetic field.

The invention has for its object to provide an ion source for slow-ion sputtering, in which only ions having low primary energies are formed and high ion flows are obtained.

In an ion source for slow-ion sputtering, in which the ions are produced in a non-self-sustained discharge occurring at least partly in a magnetic field, the anode is formed, in accordance with the invention, by an open cylindrical sheath accommodating at one end the filament cathode, while in the discharge path between the anode

2

and the cathode prevails a magnetic field of a few hundred gauss in an axial direction relative to the anode. Owing to the relative disposition of the two electrodes in the magnetic field a very intensive discharge is produced by anode voltages of at the most 30 to 40 v. at an argon pressure of about 10^{-3} torr, said discharge being of the order of 10 A. in accordance with the dimensions. The plasma of this discharge extends from the open end of the anode opposite the cathode in the vacuum space and from this plasma the ions having primary energies always at the most equal to the anode voltage, i.e. 30 to 40 v. can be directed to the target plates by electric fields and, if desired, by magnetic fields. The magnetic field of the main discharge, which is fairly weak beyond the anode, affects the path of the ions and of the sputtering products only to a slight extent. The disposition of the targets and of the substrate may therefore be rather arbitrary.

In order to protect the sputtering space from evaporation products of the cathode, a screening plate at a floating potential is arranged in front of the cathode, viewed in the direction towards the sputtering space. Also on the other side of the cathode a screening plate is provided, which is preferably connected with a beaker surrounding the anode. The two screening plates are preferably connected with each other. The low anode voltage ensures that no uncontrolled sputtering of the apparatus occurs, whereas a plasma for the desired sputtering is available with high intensity.

The invention will be described more fully with reference to the drawing, which shows schematically an ion source embodying the invention.

The filament cathode 1 is arranged at one end of the cylindrical anode 2 formed by a copper tube traversed by a coolant; 3 designates a screening plate, connected by two supporting rods 5 with the second screening plate 4. The plate 4 holds the copper screening beaker 6. All electrodes are held by through-connections 7 formed by rods or copper tubes, which are fastened in glass tubes 8 to the supporting plate 9. The supporting plate 9 is secured in flange 10, which is bolted to the flange 11 of the housing part 12. A magnetic coil 13 surrounds the centre of the anode. At the side of the axis of the anode 2, the target 14 is arranged and opposite the latter the substrate (not shown). An electric screen is designated by 15 and an auxiliary magnet by 16.

If an argon pressure of 10^{-3} torr prevails in the discharge space and if the intensity of the magnetic field is 500 gauss, the discharge current is 12 A. with an anode voltage of 30 v. The anode 2 has a diameter of 6 cms. and a length of 10 cms. The cathode 1 has a heating energy of 250 w.

With a target voltage of -300 v., target currents of 20 ma./cm.² can be attained so that high rates of sputtering can be obtained.

What is claimed is:

1. An ion source for slow-ion sputtering of an object at a given object position, comprising an anode formed as a cylindrical sheath, a cathode located at one end of the anode, a screening plate located between the cathode and the object position to be sputtered, said screening plate blocking a direct path between said cathode and said object position, said object position being located beyond the other end of the anode, and means for producing a magnetic field, said magnetic field extending axially with re-

spect to the anode and being a few hundred gauss in the discharge path between the cathode and the anode.

2. An ion source as claimed in claim 1, further comprising a second screening plate opposite the first screening plate, said cathode being located between said first and said second screening plates and said first and said second screening plates being at a floating potential.

3. An ion source as claimed in claim 2, further comprising a screening cylinder surrounding the anode, said screening cylinder being fixed in position by said second
